Inventor
Vennie Jacoby
By his Attorney
Merchant & Tilgore

UNITED STATES PATENT OFFICE.

VENNIE JACOBY, OF FULDA, MINNESOTA, ASSIGNOR TO GEORGE BROWNING, OF PARK RAPIDS, MINNESOTA.

PLIERS.

Application filed July 29, 1922. Serial No. 578,437.

To all whom it may concern:

Be it known that I, VENNIE JACOBY, a citizen of the United States, residing at Fulda, in the county of Murray and State of Minnesota, have invented certain new and useful Improvements in Pliers; and I do hereby declare the following to be a full, clear, and exact description of the invention, such as will enable others skilled in the art to which it appertains to make and use the same.

My invention has for its object to provide a simple and efficient pair of pliers that are easy to operate and hold closed while gripping an object, and to this end the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in elevation and partly in section illustrating the improved pliers closed;

Fig. 2 is a view corresponding to Fig. 1 with the exception that the pliers are open and certain parts broken away;

Fig. 3 is a transverse section taken on the line 3—3 of Fig. 2; and

Fig. 4 is a detail view in section taken on the line 4—4 of Fig. 2.

The improved pliers comprise a pair of jaws 5 and a pair of handles or levers 6. The jaws 5 are hollow with the exception of openings in which the handles 6 work, and are pivotally connected at 7 between said handles. In the free or outer end portion of the jaws 5 are secured jaw facings 8 rigidly secured in position by rivets 9 and have at their outer ends, contacting gripping surfaces 10. Inward of these surfaces 10 the jaw facings 8 are provided with tooth-equipped concave gripping surfaces 11. These jaw facings 8 are also provided with internal convex cam surfaces 12 which extend substantially parallel to the gripping surfaces 11.

The handles 6 are pivoted at 13, one to each of the jaws 5 inward of the gripping surfaces 11 and to ears 13^a on the jaw facings. Said handles 6 are provided with claws 14 in crossed relation. Said claws 14 are provided with concave surfaces 15

which rest upon the convex cam surfaces 12 with freedom for sliding movement thereon during the opening and closing movement of the jaws 5. A leaf spring 16 is secured to the outer edge portion of each handle 6, extends with the respective jaw 5, and bears against the inner wall thereof. These springs 16 are under strain to open the jaws 5.

The jaws 5, from their pivots 7 to their outer ends, are relatively long so that their co-operating gripping surfaces 10 and 11 have substantially parallel movement during the opening and closing movement of the jaws 5. The relative arrangement of the pivotal connections between the handles 6 and the jaws 5 and the action of the claws 14 on said jaws make a very powerful pair of pliers. After an object has been gripped by the pliers and affords a base of reaction, the pliers may be held closed by simply taking hold of the outermost handle, in respect to the direction of the movement of the pliers tending to turn said object, and drawing said handle in said direction. It will thus be seen that the pliers may be easily held gripped onto an object without any effort on the part of a mechanic so that he may give his entire attention to work being performed with his other hand.

The improved pliers are especially well adapted for use while working on an automobile, and in actual usage have proven highly efficient for the purpose had in view. It is, of course, understood that the gripping surfaces of the pliers may take various different forms.

What I claim is:

1. A pair of pliers comprising a pair of pivotally connected jaws, and a pair of handles, one of said handles being pivoted to one of said jaws and having a claw engageable with a cam surface on the other jaw for closing the jaws.

2. A pair of pliers comprising a pair of pivotally connected hollow jaws, and a pair of handles, one of said handles being pivotally connected within one of said jaws and having a claw working in the other jaw and engageable with a cam surface formed thereon for closing the jaws.

3. A pair of pliers comprising a pair of pivotally connected hollow jaws, and a pair of handles, one of said handles being pivot-

ally connected within one of said jaws and having a claw extending into the other jaw and engageable with a convex cam surface formed thereon for closing the jaws.

5. A pair of pliers comprising a pair of pivotally connected jaws, and a pair of handles pivoted, one to each of said jaws, said handles having claws engageable with cam surfaces on the opposite jaws from which they are pivoted for closing the jaws.

5. A pair of pliers comprising a pair of pivotally connected jaws, each of which is provided with a convex cam surface, and 15 a pair of handles pivoted, one to each of the jaws and provided with claws having concave surfaces engageable with the convex cam surfaces on the opposite jaws from which the handles are pivoted for closing 20 the jaws.

6. A pair of pliers comprising a pair of

pivotally connected hollow jaws having contacting surfaces at their outer ends, tooth-equipped concave surfaces inward of said contacting surfaces, said jaws also having convex internal cam surfaces which extend substantially parallel to said tooth-equipped surfaces, and a pair of handles pivotally connected, one in each of said jaws and having claws with concave surfaces engageable with the convex cam surfaces on opposite jaws from which the handles are pivoted for closing the jaws.

7. The structure defined in claim 6 in which each of said handles is provided with 35 a spring engageable with the jaw to which the respective handle is pivoted and under strain to hold the jaws open.

In testimony whereof I affix my signature.

VENNIE JACOBY.
